UNITED STATES PATENT OFFICE

HAROLD H. ROBINSON, OF OPALOCKA, FLORIDA, ASSIGNOR TO CURTISS AEROCAR COMPANY, INC., OF OPALOCKA, FLORIDA, A CORPORATION OF FLORIDA

DESIGN FOR A TRAILER

Application filed March 2, 1933. Serial No. 47,378. Term of patent 14 years.

To all whom it may concern:

Be it known that I, HAROLD H. ROBINSON, a citizen of the United States, residing at Opalocka, in the county of Dade and State of Florida, have invented a new, original, and ornamental Design for a Trailer, of which the following is a specification, reference being had to the accompanying drawing, forming a part thereof.

Referring to the drawing:

Fig. 1 is a side view of the trailer,

Fig. 2 is a top view thereof, and

Fig. 3 is a rear view of the roof portion of the trailer.

I claim:

The ornamental design for trailer as shown.

HAROLD H. ROBINSON.
